(57) **CLAIM**

The ornamental design for electrical connector, as shown and described.

DESCRIPTION

FIG. 1 is a front perspective view of an electrical connector, including a top portion depicted in dashed lines, showing our new design;

FIG. 2 is a front perspective view of the electrical connector, without the top portion;

FIG. 3 is a top plan view of the electrical connector in FIG. 2;

FIG. 4 is a front elevation view of the electrical connector in FIG. 2;

FIG. 5 is a right side elevation view of the electrical connector in FIG. 2;

FIG. 6 is a left side elevation view of the electrical connector in FIG. 2;

FIG. 7 is a rear elevation view of the electrical connector in FIG. 2; and,

FIG. 8 is a bottom plan view of the electrical connector in FIG. 2.

The structural features shown in broken lines are for illustrative purposes only and form no part of the claimed design.
